UNITED STATES PATENT OFFICE.

WALTER F. KOKEN, OF ST. LOUIS, MISSOURI, ASSIGNOR TO KOKEN BARBERS SUPPLY COMPANY, OF ST. LOUIS, MISSOURI, A CORPORATION OF MISSOURI.

DESIGN FOR A CHAIR.

44,006.

Specification for Design.

Patented May 13, 1913.

Application filed February 17, 1913. Serial No. 749,044. Term of patent 14 years.

To all whom it may concern:

Be it known that I, WALTER F. KOKEN, a citizen of the United States, residing at the city of St. Louis, State of Missouri, have invented a new, original, and ornamental Design for Chairs, of which the following is a specification, reference being had to the accompanying drawings, forming part thereof.

Figure 1 of the drawings is a perspective view of a chair showing my new design; and Fig. 2 is a rear elevation thereof.

The characteristic and dominant feature of this design resides in the combination of the chairback having a circular area with a seat having a circular area and a seat-support of circular form and a circular pedestal and circular base. The main body of the back is, moreover, ornamented by an encircling band. Preferably the center of the back will project forward into a different vertical plane from said band.

Another element of this design is the rib-

like embossing upon the periphery of the said seat-support and pedestal.

Minor details of ornamentation will be found in the shape of the hand-grips at the front end of the arms, said hand-grips being freed from sharp corners and being rounded as shown in the drawings and having a rise toward the front end thereof.

Other details of ornament are the peculiarly-shaped brackets for holding the back and connecting the same to the other parts of the chair.

I claim:

The ornamental design for a chair as shown and described.

In testimony whereof, I hereunto affix my signature in the presence of two witnesses.

WALTER F. KOKEN.

Witnesses:

ARTHUR H. NEWMAN,
A. T. FREGLING.
